WALL STRUCTURES FOR ELECTROLYTIC CELLS

Joshua Szechtman, Byram, Conn., assignor to Amroc Incorporated, New York, N. Y., a corporation of Michigan

Application November 4, 1953, Serial No. 390,194

5 Claims. (Cl. 204—219)

This invention relates to electrolytic cells of the mobile mercury cathode type, and is particularly concerned with the wall structure of the primary section of such cells.

In mercury cells used for the electrolysis of alkali metal chlorides and for the production of chlorine gas, the primary section is usually constructed in the form of a long and narrow trough-shaped vessel. These vessels are normally slightly inclined with respect to the horizontal so that when in operation a thin film of mercury flows along the bottom of the section. Brine or other electrolyte flows on top of the mercury, and during the operation of the cell, wet chlorine gas is produced and collects in the space in the cell above the brine.

The bottom of the vessel, along which the mercury flows, is generally constructed of steel, but the faces of the sidewalls which come in contact with the brine and the chlorine gas must be constructed or lined with a material resistant to the corrosive action of the brine and of the wet chlorine gas. Hard rubber is normally employed for this purpose.

Various non-corrosive sidewall constructions have been devised for resisting this corrosive action. Principally, they have been concerned with the application of linings, commonly of hard rubber, to the sidewalls, which linings extend down below the brine level, to assure that neither the brine nor the chlorine can get beneath the lining and attack the wall in back of it. This is difficult to do, and it is more difficult still to prevent mercury from creeping past the edges of the lining. Depending on the cell construction, the mercury, due to its tendency to creep through small spaces, leaks out and drops on the floor, or seeps up under the linings. The loss of mercury in these manners can often go by unnoticed and explosions can result due to insufficient mercury coverage on the bottom of the cell section or vessel.

The construction of the present invention obviates the foregoing and other drawbacks of prior constructions, and does so in a simple, straightforward, fool-proof manner. The invention construction is designed to prevent any leakage of mercury past the walls of the cell, but should such leakage occur, the invention furnishes safeguards against any damage being caused. In fact, the invention construction not only provides for containing any mercury which may possibly leak out of the actual cell area, but it also provides for the mercury which has leaked out forming a seal to stop continuation of the leakage.

The cell of the invention, besides being more effective than those heretofore employed insofar as prevention of leakage and avoidance of the results thereof is concerned, is also of more economical construction. Previous practices have rendered it necessary to accurately machine the edges of the bottom surface of the cells. The necessity of such machining is obviated by the construction of the instant invention, for the type of edge seal requiring such machining is no longer needed. The mercury itself will form a seal if necessary.

The cell of the invention also simplifies repair and replacement of the sidewalls as well as greatly reducing the cost of such work. It is merely necessary to remove wall

2

elements and renew the coverings on them or effect other repairs to them when such becomes necessary. Heretofore, practically the whole trough had to be relined or replaced when repairs to the linings were needed. Such is no longer the case.

It is accordingly the principal object of the invention to improve on the construction of the primary section of electrolytic cells used in the production of chlorine.

Another object is to improve on the relationship between sidewalls and bottom of such cells.

Another object is to reduce the amount of machining necessary in forming such cells.

Still another object is to form a tight seal against the leakage of mercury from such cells.

15 A further object is to provide for the catching and retaining of any mercury which may possibly leak from such cells.

And a still further object is to provide for the employment of mercury which may leak from such cells to form 20 a seal against any further leakage.

A still further object is to reduce the work and expense involved in reconditioning such cells.

Other and more detailed objects will in part be obvious and in part be pointed out as the description of the invention, taken in conjunction with the accompanying drawing, 25 proceeds.

In that drawing:

Figure 1 is a diagrammatic plan view, with a transverse fragment broken away to save space, of a cell in accordance with the invention, illustrating the relationship of the parts thereof.

Figure 2 is a half transverse section and a half end elevation of such a cell, on enlarged scale, with the center portion thereof broken away to save space and illustrating the preferred embodiment of the invention.

Figure 3 is a view similar to the lefthand portion of Figure 2 illustrating one modification of the invention; and

Figure 4 is a similar view of another modification.

The primary cell section here being considered would 40 generally be in the form of an I-beam providing a trough between one pair of ends of the I, or would be formed to provide a similar solid trough-shaped channel. In the case of an I-beam, the web of the beam, or in the case of a trough-shaped channel, the bottom of the channel, would 45 serve as the bottom of the vessel along which the mercury flows. The cell of the invention as illustrated is shown as being formed from an I-beam section, but it is of course to be understood that such is for illustrative and not limiting purposes. The base of the trough is shown at 50 1 in Figure 2, and the integral upstanding sides thereof, hereinafter for convenience referred to as "side rails" are shown at 2 and 3. It is of course to be understood that the cell is long and narrow, and a section has been broken away across the cell in Figure 1 to illustrate this. Also 55 the width of the cell is substantially greater than is shown in Figure 2. There a center section has been broken away since it is not needed for an understanding of the invention.

In the Figure 1 showing, the cell is indicated as closed 60 at its ends 4 and 5. The end 4 extends into an end box 6 which serves for the introduction of the mercury into the cell, while the box 7 at the other end enables depleted brine and mercury which has picked up some amalgam to flow out into the secondary section. These 65 features form no particular part of the instant invention, so no further discussion of them is necessary.

Reverting to Figure 1, it will be seen that the cell is provided with a pair of sidewalls 8 and 9 which are spaced inwardly from the side rails 2 and 3 respectively, and 70 which extend throughout the length of the cell. The sidewalls 8 or 9 are both of the same construction, so only one need be described in detail.

In the first place, the sidewalls 8 and 9 as shown, are formed as U-shaped members having a base 10 which forms the vertical wall, top and bottom flanges 11 and 12, and end flanges 13 and 14. The top flange 12, as here shown, has a right angle bracket 15 applied thereto, which bracket has an upstanding portion 15' inset from the face of the wall 10 for the reception and seating of a cover to be hereinafter described. The inner surface of the wall 10, being the one on the side of the brine and gas in the cell, is faced with a hard rubber covering 16. This covering commences at 17 underneath the flange 11 and extends all the way up the surface of the wall 10 as seen at 16. The covering turns inwardly along the flange 12 at 18, extends up the portion 15', and is beaded around the end thereof at 19. This rubber covering is suitably secured to the steel of the rail member to adhere tightly thereto.

A gasket strip 20, preferably of softer material than the wall covering 16-17, is located between the portion 17 and the upper surface 21 of the base 1 of the cell. This strip runs full length of the sidewall, as does the hard rubber wall covering.

The bottom flange 11 is perforated at closely spaced positions 22 along its length to receive studs 23. The studs 23 are preferably welded to the base 1, though they may be otherwise suitably secured thereto. Extending up through the gasket 20, the covering 17 and the perforations 22, they receive washers 24 and nuts 25 for clamping the flange 11 and cover portion 17 against the gasket 20. When all of the nuts 22 are tightened down, a seal is provided against leakage of mercury on the surface 21 outwardly of the walls 8 and 9.

In the unlikely event that the seal formed by the gasket material 20 should fail and any mercury should thus leak out to the position 26, protection would be afforded against loss of mercury and against possible explosions due to insufficient mercury covering the bottom 21. This protection would be effected by the mercury which first leaks out since that portion could not escape beyond the side rail 2 so would collect at the position 26. The leaking mercury would thus build up at the position 26, or in the trough like chamber provided between the inner surface 27 of the side rail 2 and the opposed portions of the sidewall with its covering material. Once the mercury at the position 26 has built up sufficiently to equal the level of mercury on the surface 21, the part that had leaked out would serve as a seal against further leakage of mercury. Since mercury is continuously flowing over the surface 21 and is replenished from the secondary cell, the level on the surface 21 will be retained.

Should the gasket material 20 or any of the covered hard rubber 16, 17, 18 fail in any respect, it would merely be necessary to remove the side rail and replace the defective covering layer or gasket. Furthermore, this construction has the substantial advantage of rendering unnecessary the careful machining of the base of the cell, and particularly the position where the base joins the sidewall, which heretofore had to be most accurately formed to receive the lower end of the sidewall covering.

The cell as here shown is provided with a cover 28 seated on the hard rubber portion 18 and sealed along its side by means of a gasket 29 and a liquid seal 30. This, however, is merely provided to complete the illustration and forms no particular part of the instant invention since covers of various other forms could be applied.

Suitable flanges 31 and 32 are provided for securing the ends such as 4 and 5 in place on the cells. Those ends are provided with hard rubber coverings like the covering 16 where they are exposed to the brine or gas.

The brackets 33 are illustrated for the partial mounting of the cell but, in and of themselves, they form no particular part of the invention.

An alternate form of sidewall construction and clamping thereof is shown in Figure 3. Here again an I-beam

construction is shown having a base 40 and side rails 41, it being understood that both sides of the cell would be the same as the single one here shown. The actual sidewall here is in the form of an L, having a vertical portion 42 and an outwardly extending horizontal top portion 43. A hard rubber covering 44 is applied to the sidewall, commencing at 45 on the outside of that wall, turning around the rounded bottom edge 46 of the same, as shown at 47, and terminating at 48 where it overlies a portion of the top 43. A relatively soft gasket 50 is seated on the bottom surface 51 of the cell and is engaged by the portion 47 of the hard rubber liner.

A tight joint is formed in the region of the gasket 50 by means of the bolt 52 whose head engages the upper surface 53 of the portion 43 and whose shank passes down through the perforation 54 so that the threaded portion 55 of the bolt is in threaded engagement with the opening in a mounting rail 56. The mounting rail 56 is preferably welded at 57 to the inner surface 58 of the side rail 41 and extends along the full length of that side rail. The bolts 52 are closely spaced along the portion 53 of the sidewall like the bolts 23 of Figures 1 and 2. Thus, when the bolts 52 are turned down they carry the sidewall 42 down with them to compress the gasket 50 and make a tight seal beneath the wall along the length thereof.

Again, should the gasket 50 fail, the mercury which leaks past it would be trapped at 59 in the trough like chamber between the side rail 58 on one hand and the gasket 50 and sidewall 42 on the other hand. As in the previous form, this mercury could not escape, but would build up and thus form an effective seal. Removal of the sidewall and replacement of the same, as well as that of the gasket 50, can be easily effected when desired, and the need for fine machining of any portion of the surface 51 is eliminated.

A further modified clamping arrangement is illustrated in Figure 4 where again a fragment of an I-beam construction is shown as the basic element. This construction provides a cell base 60 and side rails 61 from which a mounting rail 62 projects, being welded at 63, as is the rail 56 in the Figure 3 form. Here, however, the bolt 64 is in threaded engagement with the mounting rail 62 at the position 65. The bolt 64 is thus screwed down through the mounting rail 62 and has its bottom end 66 engaged with the upper surface of an L-clamp 67.

The horizontal portion of the L-clamp 67 engages the horizontal outwardly extending portion 68 of the sidewall 69 to force the same downward. The downward extending portion 70 of the clamp plate 67 engages at 71 with the curved corner between the bottom 72 of the cell and the inner wall 73 of the side rail 61. Thus the clamping force is directed against the sidewall portion 68.

Again, the sidewall 69 is suitably covered with a hard rubber covering 73 which extends down around portion 68 at 74 and terminates at 75 in an upturned portion lying against the outer end surface of the portion 68. A suitable gasket 76 is provided between the hard rubber portion 75 and the bottom 72 of the cell.

The gasket 76 extends along the whole length of the sidewall, as does the clamping plate 67. The bolts 64 are positioned in spaced relation along the length of the cell like the bolts 23 and 52 previously described. Thus, when the bolts 64 are turned down against the clamping plate 67, the latter engages the upper surface of the wall portion 68, and squeezes the gasket 76 as well as the hard rubber portion 74 to provide a tight seal.

Again, should the gasket 76 or the portion 74 fail, the mercury will leak into and be caught in the trough at the position 77 where it will build up until it provides a hydrostatic seal against further leakage.

From the foregoing description of the preferred and alternate embodiments of the invention, it will be appreciated that the objects thereof are achieved by the novel constructions disclosed. It is of course to be understood

that the specific wall structures illustrated are shown for illustrative and not limiting purposes, since one skilled in the art would appreciate how different wall structures and different manners of clamping the same in position could be devised without departing from the spirit or scope of the invention. Speaking more generally, it is obvious that certain changes may be made in the constructions above described, and further embodiments of the invention could be made without departing from the scope thereof. It is thus intended that all matter contained in the above description or shown in the accompanying drawing shall be interpreted as illustrative and not in a limiting sense.

Having described my invention, what I claim as new and desire to secure by Letters Patent is:

1. In electrolytic cell construction, an integral one-piece elongated steel member of U shape in cross section providing a base with a pair of upstanding side rails extending therealong, the upper surface of said base between said side rails lying substantially in a single plane and being devoid of recesses, individual side walls carried by said base within said rails, extending upwardly from said surface and extending substantially parallel with respect to said rails, resilient gasket means extending between the bottom ends of said side walls and said surface, and clamping means acting between said member and said side walls and engaging said side walls to secure said side walls in place, force the same towards said planar upper surface and to compress said gaskets, said side walls being in spaced relationship with respect to said side rails and cooperating with said side rails and with the included

portions of said upper surface to form elongated troughs.

5 2. In electrolytic cell construction as in claim 1, said clamping means including bolts secured to said upper surface and extending upwardly therefrom, and means on said side walls for receiving said bolts.

3. In electrolytic cell construction as in claim 1, said clamping means being carried by said side rails and engaging projections on said side-walls.

4. In electrolytic cell construction as in claim 1, said clamping means including clamping plates engaging portions of said side walls and clamping members carried by said side rails and engaging said clamping plates.

10 5. In electrolytic cell construction as in claim 1, said clamping means including laterally extending flanges carried by said side walls and clamping members carried by said side rails and engaging said laterally extending flanges.
